UNITED STATES PATENT OFFICE.

IRWIN H. KRAVITT, OF PHILADELPHIA, PENNSYLVANIA.

DESIGN FOR A LAMP STAND.

Application filed April 30, 1927. Serial No. 21,799. Term of patent 14 years.

To all whom it may concern:

Be it known that I, IRWIN H. KRAVITT, a citizen of the United States, residing at Philadelphia, in the county of Philadelphia and State of Pennsylvania, have invented a new, original, and ornamental Design for Lamp Stands, of which the following is a specification, reference being had to the accompanying drawing, forming part thereof.

The figure is a perspective view of a lamp stand, showing my new design.

What I claim as new and desire to secure by Letters Patent, is:

The ornamental design for a lamp stand as shown.

IRWIN H. KRAVITT.
